FLEXIBLE LIGHT SOURCE
James F. Motson, 798 Welsh Road,
Huntingdon Valley, Pa.
Filed May 18, 1959, Ser. No. 813,740
2 Claims. (Cl. 313—108)

This invention relates to light sources and in particular to light sources which are packaged to be compact and flexible.

Heretofore light sources used in maintenance work have been generally of the non-flexible type. For instance, customarily people doing maintenance or repair work have depended on a drop light, or the everyday flashlight, to provide a source of light at the area upon which the work was being done. Such light sources have been only partially satisfactory because some areas were inaccessible due to the lack of room for advantageous placement of the bulky package of the drop light, or the flashlight and, thus, these areas could not be illuminated.

Efforts have been made to provide flexible sources of light, for instance in the form of a section of flexible cable. Such cable, while flexible, does have certain rigid characteristics, such as BX cable. In this last-mentioned arrangement a small bulb is held on the end of the cable. While such an arrangement does provide light into areas which may be inaccessible to the drop light, or the flashlight, this cable light is, of course, limited by the thickness of the cable and the bulb.

In the field of ornamental lighting, novelty lighting, or novel utility lighting heretofore the efforts have been confined to different arrangements of incandescent light bulb packages, such as the "bubblers" for Christmas trees; or in the extreme, neon lights, as used in advertising signs. Such novelty lighting is unsatisfactory in that there is relatively heavy electrical power consumption and distracting electrical components, such as sockets, or taped joints, which take away from decorative appeal of the ornament.

It can be recognized that a light source which is extremely flexible and compact so as to be shaped irregularly for positioning in highly inaccessible areas and yet not be limited by cable and bulb thickness would be highly desirable, especially in maintenance work. It can also be recognized that a novel ornament device, which can assume virtually any shape, which is self-illuminating for use in decorations such as on Christmas trees, or in decorative utility such as door bell name plates, which would consume very little electrical power would be highly desirable.

It is therefore an object of the present invention to provide an improved compact and flexible light source.

It is a further object of the present invention to provide an ornamental omni-directional or directed light source which can be formed into substantially any particular shape.

In accordance with a main feature of the present invention there is provided a layer of electroluminescent material which is flexible, first and second layers of flexible electrical conducting material (with at least one layer being transparent), bonded to the opposite sides of said electroluminescent layer to provide a source of light mounted in or on a thin, flexible housing.

In accordance with another main feature of the present invention the layers of the last-mentioned feature can be formed according to any particular shape to provide a self-illuminating ornament device.

In accordance with another main feature of the present invention both of the electrical conducting layers of the first feature above can be transparent to provide an omni-directional light source.

The foregoing and other objects and features of this invention will be best understood by reference to the fol-

2

lowing description of the invention taken in conjunction with the accompanying drawings, wherein:

FIG. 1 is a schematic side view of the basic light source package;

5 FIG. 2 is a pictorial schematic (with an end sectional) showing the flexibility of the present inventive light source housing;

FIG. 3 shows a self-illuminating ornament;

10 FIG. 4 shows a door bell name plate utility of the flexible light source;

FIG. 5 shows a pictorial of the flexible tape light package on a drum;

15 FIG. 6 shows a pictorial of a flexible tape light package driven by sprockets.

20 Referring particularly to FIG. 1 there is shown the basic light source package. The layer 11 is a flexible strong plastic base. Such a layer can be a polyester film such as Mylar, or a plastic material such as Teflon. Both Mylar and Teflon are manufactured and sold by E. I. du Pont de Nemours and Company, Wilmington, Delaware. Although a flexible, strong plastic layer is shown at 11 it is to be understood that the basic flexible layer upon which the light source is mounted can be a flexible metal such as a sheet of aluminum. If such a metal is 25 used it serves in the dual role of being the basic building, or mounting, layer as well as the back electrical conducting layer. In the embodiment of the present invention depicted in FIG. 1 the basic building layer 11 is a flexible transparent plastic, such as Mylar, which can 30 be used in a light source providing omni-directional light.

One surface of the layer 11 is "roughed" to provide good adherence and to this "roughed" side there is bonded a layer 13 of electroluminescent material. The electroluminescent material can be a combination of any of the 35 well-known electroluminescent phosphors such as zinc sulphide, with a suitable activator such as copper powder, held in an appropriate vehicle such as epoxy resin. Other phosphors, activators and vehicles can obviously be used to effect different degrees of brightness, lamp life, and 40 light color.

The layers 15 and 17 are the electrode layers necessary to provide an electrostatic field across the electroluminescent layer 13 to cause the emission of light therefrom. The layers 15 and 17 can take many forms, such as stainless steel mesh, if the electrode layers are to be transparent; or a conducting metal paint, if transparency is not a requirement; or vaporized metal which also permits transparency. In the preferred embodiment a coating of 45 epoxy resin is applied to the electroluminescent layer 13, and a layer 17 of stainless steel 260 mesh is pressed into the epoxy resin, then the package is cured. If the final product is to be an ornament having omni-directional light then layer 15 is also, in the preferred embodiment, a layer of stainless steel 260 mesh, pressed into an epoxy 50 resin and cured. On the other hand, if the final product is to have directed light, such as the maintenance light of FIG. 2 or the tape of FIGS. 5 and 6, then one electrode such as the layer 15 of FIG. 1 may be a layer of reflecting, conducting metal paint such as silver metal 55 paint. Silver metal paint has the advantages of providing good conductivity and also of reflecting light.

In FIG. 1, for purposes of clarity in connection with the above description there is not shown any encapsulating layer as is shown by the potting material layer 19 of 60 FIGS. 2 and 3. Such an encapsulating layer of course would be present with the embodiment of FIG. 1 in actual use to prevent electrical shocks to the user of the light.

In FIG. 2 the flexible light is shown pictorially to be 65 partially rolled for placement into an area heretofore inaccessible. The layers 11, 13, 15 and 17 are, in the preferred embodiment, as described in connection with

FIG. 1. The encapsulating material 19 can be, in addition to the popular potting materials, two layers of Mylar, or polyester film, which are sealed at the edges. The encapsulating material needs to be transparent, have high electrical insulation qualities, and flexible. The light packages of FIGS. 1 and 2 show the electrode layers 15 and 17 connected to a source of A.-C. voltage 21.

In FIG. 3 the feature of particularly shaping the light package is depicted by a Christmas tree ornament 23, in the form of a star. The layers 11, 13, 15, 17 and 19 are again shown and are of the same material as discussed above in connection with FIGS. 1 and 2. In the ornament of FIG. 3 the electrode layers 15 and 17 would both be transparent. In addition in FIG. 3 there is shown a layer 25 of color selected photoluminescent material. The layer 25 provides a selected color to the ornament 23 in accordance with the principle discussed in my copending U.S. patent application entitled "Indicia Bearing Device," Serial No. 796,876, filed March 3, 1959. The layer 25 could in fact be multicolored layers of photoluminescent material to provide a multicolored ornament. A hook 27 is provided, connected to the plastic layer 11 for hanging the ornament. As depicted in FIG. 3 the wires 29 to the electrode layers 15 and 17 are simply connected without a socket to the parallel wire 31 available around the tree, thereby minimizing the distraction from the decoration, as suggested above, which is attributable to electrical connections. Obviously, for interchangeability of the ornament, a plug can be provided at the parallel wire 31 level. Such last-mentioned arrangement however does keep the connection away from the ornament proper to insure the full decorative effect of the ornament.

FIG. 4 shows the invention in a decorative-utility role. The name plates can be photo-printed according to the technique described in my Patent No. 2,382,806, entitled "Synthetic Plastic Articles and Methods of Making the Same," issued August 14, 1945. The name plates will then reflect some predetermined color in the natural light, for instance the color white, and at night will be illuminated with the light emitted from the light source in back of the name display plate.

In FIG. 5 there is shown the present inventive flexible light source in the form of tape 33 which is mounted on a drum 35. The drum 35 is rotated by the shaft 37, while simultaneously the numerals on the tape 33 are illuminated. The layers making up the light package (tape 33) are not shown in FIG. 5 but it is to be understood that the layers include two electrodes with a layer of electroluminescent material mounted on a flexible plastic base sandwiched between the electrodes (such as shown in FIG. 2). In addition, there is mounted over the transparent electrode an additional layer of flexible opaque material, which has numerals cut therefrom or formed therein, to enable the light to pass through in the numeral areas and thereby provide illuminated numerals. In FIG. 5 the electrical connections are not shown, for purposes of simplicity, but it is to be understood that the power supply leads are connected to a commutator arrangement to provide electrical power to the electroluminescent layer during rotation. As the drum rotates the illuminated numerals are seen in the window 39 of the housing. Such an arrangement has utility in disc-type meters where an illumination, for instance during night operations, is required.

In FIG. 6 a tape arrangement 41 of the flexible light source is shown driven by two sprockets 43 and 45 in a fashion similar to a movie projector. The tape can be extremely long. The tape 41 includes all the layers described in connection with the tape of FIG. 5, and as did the tape in FIG. 5, the tape 41 includes an additional layer of opaque flexible material such as black Mylar, with numerals cut therefrom. In addition the tape shown in FIG. 6 has found great utility wherein there is also provided a multicolored layer of photoluminescent material

disposed beneath the opaque material, that is, between the transparent electrode of the electroluminescent lamp and the opaque material with the "cut-out" letters. The utility becomes apparent if, for instance, the tape 41 number thirty-two represented a critical temperature and the sprockets 43 and 45 were driven by a temperature control. The photoluminescent material can be color arranged so that as the tape number forty appeared a warning color also would be seen and the numbers down to 32 would appear in greater degrees of severe warning colors (pink to red). As was suggested in connection with the description of FIG. 5, the tape 41 is connected electrically through a commutator arrangement to provide the A.-C. voltage across the electroluminescent layer of the tape.

While I have described above the principles of my invention in connection with specific apparatus, it is to be clearly understood that this description is made only by way of example and not as a limitation to the scope of my invention as set forth in the objects thereof and in the accompanying claims.

I claim:

1. A light source having a flexible housing comprising a layer of polyester film having first and second sides; a plurality of electroluminescent phosphors held in a flexible layer of epoxy resin material, said layer of epoxy resin having first and second sides and having its second side bonded to the first side of said polyester film; a first flexible electrode means bonded to said first side of said layer of epoxy resin; a second flexible electrode means bonded to said second side of said polyester film, at least one of said electrodes being transparent; and means coupled to said first and second electrode means for connecting thereacross a source of voltage to pass an electrostatic field through said electroluminescent material for causing radiation of luminous energy therefrom.
2. A light source which is flexible comprising: a layer of polyester film having first and second sides, said first side being formed rough to provide a good bonding surface; a plurality of electroluminescent phosphors held in a flexible layer of epoxy resin material, said layer of epoxy resin having first and second sides and having its second side bonded to the first side of said polyester film; a first flexible transparent electrode means having one side secured to said first side of said layers of epoxy resin; a second flexible electrode means secured to said second side of said layer of polyester film; means coupled to said first and second flexible electrodes for connecting thereacross a source of voltage to pass an electrostatic field through said electroluminescent phosphors for causing radiation of an exciting light therefrom;
3. A flexible layer of color selected photoluminescent material having a first and second side with its second side bonded to the other side of said first flexible transparent electrode to receive and be excited by said exciting light, thereby in turn to radiate a fluorescent light having a frequency significant of said selected color, to be visible from the first side of said photoluminescent material.
